UNITED STATES PATENT OFFICE.

JOHN H. GILES AND DONALD M. GILES, OF PHILADELPHIA, PENNSYLVANIA.

TRIP MECHANISM FOR DYEING MACHINES.

Application filed April 19, 1922. Serial No. 555,564.

To all whom it may concern:

Be it known that we, JOHN H. GILES and DONALD M. GILES, both residing at Philadelphia, county of Philadelphia, and State of Pennsylvania, have invented certain new and useful Improvements in a Trip Mechanism for Dyeing Machines, of which the following is a specification.

My invention relates to dyeing machines and more especially to those of the type in which yarn in the form of skeins is treated by being passed through a vat containing dye liquor. In such machines it is customary to support the yarn in the skein form between two series of yarn sticks mounted horizontally in inner and outer frames, the frames being in the form of wheels and being supported in a vat. In these machines the skein supporting structure is movable as a whole into and out of the dye vat and the sticks are removable from the heads of the frames so that the skeined yarn may be placed in position thereon. When the yarn is supported on the sticks in the usual manner the supporting shaft is revolved so that successive sticks about the periphery of the supporting members will be passed through the liquor. In this way successive strands are immersed in the dye and in order that the entire mass of yarn in a single skein may be treated so that the color will be even, it is necessary that the skein be moved on the supporting member. This is accomplished by providing a suitable star wheel or ratchet movable with each stick of one series and operated by a trip mechanism so that as each star wheel passes beneath the trip, it will be given a partial rotation, this causing the yarn to be moved relative to the sticks so that a different portion of the skeins will be immersed as the supporting frames are revolved. It is necessary that the trip have a resilient mounting so that should the yarn become tangled on a pair of sticks in such a way to prevent the partial rotation of the sticks the trip will yield so that the yarn will not be broken.

It will be understood, of course, that though the machine is regularly revolvable in a single direction only, it sometimes happens that when it is brought to rest, the shaft will be moved a short distance in the reverse direction. It is necessary in such event that the trip be of such form that it will be thrown out of action so as not to cause the star wheel to be reversely rotated

inasmuch as this will have a tendency to tangle the yarn strand.

One object of this invention, therefore, is to provide a new and improved trip mechanism for a dyeing machine of the class described, such trip mechanism providing means for exposing successive portions of the yarn skeins to the action of the dye liquor and having a positive action when the machine is rotated in one direction, except in the case of undue stress, and being thrown out of action when the machine is reversed.

Another object of the invention is to provide a trip mechanism for a dyeing machine of the class described, such mechanism providing a simple and effective means for exposing successive portions of the skeins to the action of the dye liquor and being so arranged as to prevent undue stress being put on the skeins and to prevent the movement of the skeins in the reverse direction.

Another object of the invention is to provide a new and improved trip mechanism for a dyeing machine of the class described which shall be simple in construction, formed of a few parts not readily made ineffective by wear and one which shall be cheaply constructed.

Other objects and aims of the invention, more or less specific than those referred to above, will be in part obvious and in part pointed out in the course of the following description of the elements, combinations, arrangements of parts and application of principles, constituting the invention; and the scope of protection contemplated will be indicated in the appended claims.

With this and other objects in view, reference is now made to the drawings in which are shown various preferred forms of embodiment of my invention.

In the drawings Figure 1 represents a vertical cross-sectional view of a dyeing machine showing my invention in place.

Figure 2 is a front view in detail of the various parts constituting my invention.

Fig. 3 is a side view in detail of the construction otherwise illustrated in Fig. 2.

Figures 4 and 5 are front and side views respectively of a modified form of my device.

Figures 6 and 7 are front and side views respectively of another modification of my invention.

With reference now to the drawings in which similar reference characters refer to

similar parts throughout the several views thereof, the reference character 1 denotes the body structure of the machine, in the bottom of which is located a semicylindrical dye 5 vat 2 supplied with dye liquor through a pipe 3 and having a suitable outlet gate 4.

Mounted in the ends of the body structure 1 in slot-like bearings 5 is a shaft 6 upon which is mounted a pair of outer frames 7 10 and a pair of inner frames 8. In Figure 1 there is shown but one member of each pair of frames and it will be understood that the structure shown in Figure 1 is duplicated at the other end of the shaft. 15 Running between the pair of heads are two rows of yarn sticks 9 and 10, the yarn sticks forming the elements of the inner and outer rows being removably mounted on star wheels 11 journaled upon the heads so that 20 the skeins may be placed thereabout, a single skein running between corresponding sticks of the inner and outer rows. When the sticks are in place with the yarn wound about them, the inner sticks are loosely held 25 in bearings in the inner star wheels while on the outer star wheels the bearings for the sticks are rigidly secured when in operative position. Loosely mounted on the shaft 6 is a guide rod 12 extending outwardly and 30 projecting through a swivel guide 13. Upon this guide rod 12, is mounted the trip mechanism at a point adjacent the row of star wheels so that the points of the star wheels 35 will be engaged thereby as the shaft 6 is revolved.

As has been explained, the shaft 6 is supported in bearings in an arcuate slot 5 to the end that the shaft with the stick supporting heads thereon may be mounted bodily 40 out of the dye vat so that the dyed skeins may be removed and new ones substituted on the sticks. By providing a loose mounting for the guide rod 12 on the shaft and using a swivel guide 13, this permits 45 the shaft with its attached members to be swung out of and into operative position without necessitating the readjustment of the trip mechanism relative to star wheels.

The general construction of the dyeing 50 machine so far described is of familiar form and is inserted herein in order that the operation of my new improved trip mechanism will be readily understood. With reference now to Figures 2 and 3, it will be seen that the trip mechanism consists of two parts, a movable arm and a resilient stop for one end of the arm. Mounted on the 55 guide rod 12 is a suitable clamp 14 on which is pivotally mounted at 15 an arm 16.

The arm 16 projects downwardly from the pivot so as to lie in the path of the outwardly extending arms of the star wheels 11. The arm 16 has an upward extension 17 and mounted on the guide rod 12 at a 60 point slightly beyond the clamp 14, is a sec-

ond clamp 18 to which is attached an arm 19. In the end of the arm 19 is secured a bolt 20 about which is coiled a spring 21 and mounted on the bolt adjacent its forward end is a stop 22 held against the under side of the arm 19 by the spring 21. The stop 22 projects downwardly and is normally engaged by the extension 17 of the arm 16. Adjacent the pivot point the arm 16 has an extension at right angles on which 75 is mounted a weight 23.

It will be seen that as the main shaft revolves in the counter clockwise direction the outwardly extending arms of the star wheels will come in contact with the arm 16. Under normal conditions the arm 16 will be held sufficiently rigidly on its pivot by means of the spring 21 and stop 22 so that the star wheel in moving past the arm 16 will be rotated by one tooth. The outer 85 sticks as will be seen have a square cross section and a partial revolution of the stick will cause the skeined yarn to be moved from one stick to the other a slight distance. It will follow from this that successive portions of the skeins will be brought to the periphery of the dyeing frame so that as the operation is continued all the yarn in the skein will be immersed in the liquor. 90

In the event that the yarn becomes tangled 95 on the sticks and is not free to move from one stick to the other, the star wheel on the stick on which the tangled skein is mounted will offer resistance to the action of the trip and when the resistance exceeds the pressure 100 of the spring against the stop, the trip will yield with a partial clockwise rotation. This forces the stop 22 to compress the spring and thus permits the point of the star wheel to ride under the trip. This will prevent 105 the yarn being broken or undue stress being put upon the star wheel and trip.

It will be understood that the star wheels are provided with ratchet devices not shown to prevent retrograde movement, and if 110 shaft 6 should be moved reversely, the teeth of the star wheels will engage the other face of the trip, which is free to move upwardly out of the way, the weight 23 restoring the trip to operative position when the star 115 wheel in question has moved from beneath the trip.

In Figures 4 and 5 a modified form of trip structure is shown. In this case the trip arm 16 is pivotally mounted on a clamp 14, located on the rod 12, the trip arm being provided with an offset weight 23. The extension 24 of the arm 16 is given a forked shape, as indicated in Figure 5 at 120 25-25, and in the fork so formed there is mounted by means of a clamp 18 on the rod 12, a downwardly extending arm 26, carrying a bolt 27 about which is coiled a spring 28. Mounted loosely on the bolt 27, near its forward end is a shield-like 125 130

stop 29, which is of such shape as to be engaged by the legs 25-25. As indicated at 30, the extension 24, which is in the nature of a follower, has a curved shape, and as the trip arm 16 is rocked upon undue stress, which would prevent the turning of the star wheel, it will be understood that the arm 16 will move on its pivot, and that the extension 24 will act against the stop 29 and force it along the bolt so as to compress the spring 28.

The curved surface of the extension 24 is of such form that the pressure which will be put against the stop 29, to press the spring, will always be a direct thrust, acting in a line parallel to the bolt. This will prevent the stop from binding against the bolt, which would result in the trip arm 16 being held in position so as to resist movement when engaged by the star wheel. Were it not for the direct thrust provided for, the binding of the stop against the bolt might result in the trip 16, causing a rotation of the star wheel when the yarn was entangled, and this might easily cause a breakage in the yarn. In the case of the reverse movement of the yarn supporting heads, the trip will be moved freely out of position, the extension 24 being rocked away from the face of the stop. When the star wheel passes from under the trip in a reverse direction, the weight 23 will return the trip to operative position, with the extension 24 bearing against the stop.

In Figures 6 and 7 there is shown another form of modification in which there is provided a single clamp 31 mounted on the guide rod 12. Clamp 31 is provided with an offset extension 32 in which is mounted a pin 33. Mounted pivotally on the end of the pin 33 there is a downwardly extending trip arm 34 which projects into the path of the teeth of the star wheels and which is provided with an offset weight 35. Beyond the pivot 34 is an extension 36 and coiled about the pin 33 is a spring 37, one end of which is anchored in the extension 32, the other end 38 bearing against the extension 36 and the spring being so disposed as to offer resistance to the clockwise movement of the trip on its pivot.

The operation of the device is similar to that of the forms previously described. When the trip engages the projections of the star wheels, under normal circumstances, the wheels are revolved, but the trip yields under unusual stress. Upon movement in the reverse direction of the shaft of the dyeing machine, the trip will ride over the teeth of the star wheels and be returned to normal position by the offset weight.

It will be seen that the trip mechanism herein set forth is simple and one adapted to attain the objects mentioned. It provides a device which will rotate the star

wheels and thereby expose different portions of the yarn to the action of the dye liquor under normal circumstances, and one which will yield so as to become inoperative upon the occurrence of conditions of excessive stress upon the yarn or when the machine is reversed. The mechanism can be readily set in operative position, and once so located it requires no further attention. It will be understood also that the springs 75 may be readily replaced by others of different tension depending upon the character of the yarn to be treated. It is possible to substitute other resilient mountings in place of the springs shown, the springs being here illustrated as being a simple and convenient means of producing the desired end.

As many changes could be made in this construction without departing from the scope of the following claims, it is intended that all matter contained in the above description or shown in the accompanying drawings shall be interpreted as illustrative only and not in a limiting sense. 90

Having thus described our invention what we claim as new and desire to secure by Letters Patent is:

1. A dyeing machine comprising a dye vat, yarn stick supporting heads arranged to be revolved into the vat, stick bearing star wheels journaled in one of said heads, and having yarn supporting sticks mounted therein and rotatable therewith, and means to effect the rotation of the stick bearing star wheels in one direction, comprising a rod mounted radially relatively to the axis of said heads and a resiliently held trip arm mounted on said rod to engage said stick bearing star wheels. 100

2. A dyeing machine comprising a dye vat, yarn stick supporting heads arranged to be revolved into the vat, stick bearing star wheels journaled in one of said heads, and having yarn supporting sticks mounted therein and rotatable therewith, and means to effect the rotation of the star wheels in one direction, comprising a rod mounted radially relatively to the axis of said heads, a trip arm pivoted on said rod to engage said star wheels and a stop adapted to hold said arm in operative position under normal stresses and to yield to permit said arm to move to inoperative position under abnormal stresses. 110

3. A dyeing machine comprising a dye vat, yarn stick supporting heads arranged to be revolved into the vat, stick bearing star wheels journaled in one of said heads, and having yarn supporting sticks mounted therein and rotatable therewith, and means to effect the rotation of the star wheels in one direction, comprising a rod mounted radially relatively to the axis of said heads, a trip arm pivoted on said rod to engage 125

said star wheels, said arm being provided with a weighted extension to resist the movement of said arm in one direction on its pivot, and a stop engaging said arm to prevent its movement in the other direction under normal stresses but yielding to permit said arm to move to inoperative position under abnormal stresses.

4. A dyeing machine comprising a dye vat, yarn stick supporting heads arranged to be revolved into the vat, stick bearing star wheels journaled in one of said heads, and having yarn supporting sticks mounted therein and rotatable therewith, and means to effect the rotation of the star wheels in one direction, comprising a rod mounted radially relatively to the axis of said heads, a trip arm pivoted on said rod to engage said star wheels, a stop engaging one end of said trip arm, said trip arm being movable on its pivot away from said stop and held in operative position against normal stresses by said stop, said stop yielding under abnormal stresses to permit said trip arm to assume an inoperative position.

5. A dyeing machine comprising a dye vat, a shaft revoluble adjacent thereto, yarn stick supporting heads mounted on said shaft and arranged to be rotated into said vat, stick bearing star wheels journaled in one of said heads and having yarn supporting sticks mounted therein and rotatable therewith and means to effect the rotation of the star wheels in one direction, comprising a radial rod mounted loosely on said shaft, a trip arm pivoted on said rod and adapted to engage said bearing members, a weighted extension on said arm to bias it to operative position and a stop on said rod engaging said trip to hold it against movement to inoperative position in one direction, said trip being adapted to yield under abnormal stresses.

6. A dyeing machine comprising a dye vat, a shaft revoluble adjacent thereto, yarn stick supporting heads mounted on said shaft and arranged to be rotated into said vat, stick bearing star wheels journaled in one of said heads and having yarn supporting sticks mounted therein and rotatable therewith, and means to effect the rotation of the star wheels in one direction, comprising a radial rod mounted loosely on said shaft, a trip arm pivoted on said rod and adapted to engage said star wheels, a resiliently held stop engaging one end of said arm and holding it in operative position against normal stresses but yielding under abnormal stresses to permit movement of said arm in one direction to inoperative position, and a weighted extension on said arm to restore it to operative position when moved in the other direction.

7. A dyeing machine comprising a dye vat, a shaft revoluble adjacent thereto, yarn

stick supporting heads mounted on said shaft and arranged to be rotated into said vat, stick bearing star wheels journaled in one of said heads and having yarn supporting sticks mounted therein and rotatable therewith, and means to effect the rotation of the bearing members in one direction, comprising a radial rod mounted loosely on said shaft, a trip arm pivoted on said rod and having one end positioned to engage said star wheels, a resilient stop on said rod engaging the other end of said arm, said stop resisting the movement of the arm to inoperative position in one direction on its pivot under normal conditions, and a weighted extension on said trip to restore it to operative position when moved to such position in a direction away from said stop.

8. A dyeing machine comprising a dye vat, a shaft revoluble adjacent thereto, yarn stick supporting heads mounted on said shaft and arranged to be rotated into said vat, stick bearing star wheels journaled in one of said heads and having peripheral projections, yarn supporting sticks mounted in said star wheels and rotatable therewith, a radial rod loosely mounted on said shaft, a trip arm pivoted on said rod, one end of said trip arm adapted when in operative position to engage the projections on said bearing members, a resilient stop on said rod engaging the other end of said trip to hold it against movement out of operative position in one direction under normal conditions but yielding to permit such movement under abnormal stress, and a weighted extension on said trip to restore it to operative position when moved therefrom in the other direction.

9. A dyeing machine comprising a dye vat, a shaft revoluble adjacent thereto, yarn stick supporting heads mounted on said shaft and arranged to be rotated into said vat, stick bearing star wheels journaled in one of said heads and having peripheral projections, yarn supporting sticks mounted in said star wheels and rotatable therewith, a rod loosely mounted on said shaft radially thereof, a trip arm pivoted on said rod and adapted to engage said projections, a weighted extension on said arm to restore it to operative position when moved therefrom in one direction, and resilient means mounted on said rod engaging said trip and adapted to resist its movement to inoperative position in the other direction.

10. A dyeing machine comprising a dye vat, a shaft revoluble adjacent thereto, yarn sticks supporting heads mounted on said shaft and arranged to be rotated into said vat, stick bearing star wheels journaled in one of said heads and having peripheral projections, yarn supporting sticks mounted in said star wheels and rotatable therewith, a

- radial rod loosely mounted on said shaft, a clamp mounted on said rod, a trip arm pivoted in said clamp having one end adapted to engage said projections, a spring-held stop mounted on said rod adapted to engage the other end of said trip arm, and a weighted extension on said trip tending to hold it in engagement with said stop.
11. A dyeing machine comprising a dye vat, a shaft revoluble adjacent thereto, yarn stick supporting heads mounted on said shaft and arranged to be rotated into said vat, stick bearing star wheels journaled in one of said heads and having peripheral projections, yarn supporting sticks mounted in said star wheels and rotatable therewith, a radial rod loosely mounted on said shaft, a clamp mounted on said rod, a trip arm pivoted on said clamp having one end adapted to engage said projections, a second clamp on said rod adjacent said first-named clamp, a spring-held stop mounted in said second clamp adapted to be engaged by the other end of said trip arm, and a weighted extension mounted on said trip arm and adapted to hold it in engagement with said stop.
12. A dyeing machine comprising a dye vat, a shaft revoluble adjacent thereto, yarn stick supporting heads mounted on said shaft and arranged to be rotated into said vat, and means to affect the rotation of said yarn sticks in one direction, comprising a radial rod mounted loosely on said shaft, a trip arm pivotally mounted on said shaft, and having a forked follower, a spring-held stop mounted adjacent said follower, to be engaged by the movement of said trip on its pivot in one direction, and said follower being so formed as always to exert a thrust against said stop in a direction parallel with the axis of said spring.
13. A dyeing machine comprising a dye vat, a shaft revoluble adjacent thereto, yarn stick supporting heads mounted on said shaft and arranged to be rotated into said vat, stick bearing star wheels journaled in one of said heads and having yarn supporting sticks mounted therein and rotatable herewith, and means to affect a rotation of the star wheels in one direction, comprising a radial rod mounted loosely on said shaft, a trip arm provided with an offset weight pivoted on said rod and adapted to engage said star wheels, a forked extension on said trip arm, a stop adapted to be engaged by said extension, and held in normal position by a spring, said extension being so formed as to exert a thrust against said stop in a direction parallel with the axis of said spring when said trip arm is moved upon its pivot in one direction, and said weight tending to restore said trip arm to normal position when moved therefrom in the reverse direction.
